ATTENUATION PULSATION DAMPENER

Henry N. Wade, Los Angeles, Calif.

Application March 18, 1946, Serial No. 655,057

7 Claims. (Cl. 138—26)

1

This invention pertains to means for the suppression or the substantial elimination of pulsations in the rate of flow of gases through pipes.

The ultimate purpose of the invention is to protect from dangerous vibration pipe systems receiving the discharge from piston type compressors.

The outflow of gas from conventional piston type, positive displacement compressors is necessarily intermittent, due to the peculiarities of the compression cycle. At the end of the suction stroke the cylinder is filled with gas at approximately the suction pressure. During the earlier part of the compression stroke this gas is compressed until its pressure slightly exceeds that against the discharge valves. When this point is reached and the discharge valves lift, discharge of gas from the cylinder begins and continues to the end of the piston stroke.

Taking a commonly occurring example in which the ratio of the absolute discharge pressure to the absolute suction pressure is of the order of three to one, the piston will travel through approximately two-thirds of displacement stroke before discharge of gas begins, and consequently the entire quantity of gas delivered during a complete stroke cycle will pass out of the cylinder during a relatively short time near the end of the displacement stroke. In cases where the clearance volume is relatively large, as is common in commercial compressors, the actual delivery of gas into the discharge system may occur during only one-fourth or one-fifth of the total displacement movement of the piston.

It follows from these factors that the gas from ordinary compressor cylinders, operating at ordinary compression ratios, is delivered to the discharge system in a succession of short spurts. These spurts begin and end suddenly and, consequently, have an extreme tendency to cause vibration in the piping or other apparatus through which the gas is delivered.

In the natural gas industry, in connection with gas processing plants and gas transmission lines, difficulties due to pulsation from compressors have been greatly increased by the introduction to this industry of machines operating at relatively high speeds.

Up to about the last ten years, the types of compressors mainly used for handling natural gas operated at rotative speeds ranging from 125 R. P. M. to 200 R. P. M. With machines running at these speeds the frequency of gas pulsation was such that the piping systems usually

2

connected with them had natural frequencies outside the range of the pulsation frequencies. For this reason, a dangerous degree of vibration seldom occurred.

At the present time, however, the tendency is to the use of compressors operating at much higher speeds, up to 300 to 330 R. P. M., and also to build larger units. Whereas the amount of power applied to a single cylinder rarely went above 80 to 100 H. P. in the earlier practice, it is now not uncommon to find 500 H. P. concentrated in a single cylinder. Both of these factors have increased greatly the difficulty in designing discharge piping systems which will not be vibrated to a dangerous or even destructive extent by gas flow pulsations.

The present invention suppresses or eliminates the effect of pulsation by breaking up each advancing wave into a multiplicity of minor waves, displaced in space, the multiple waves interfering and mutually nullifying each other.

The invention is described with reference to the attached drawings, in which

Fig. 1 is a diagrammatic representation of the simplest form of the invention, illustrating the principle on which it is based;

Fig. 2 is a longitudinal section through a somewhat modified form of the invention;

Fig. 3 is a cross section taken on the line 3—3 of Fig. 2, and

Fig. 4 is a cross section through another modified form.

Referring first to Fig. 1, 10 represents the discharge end of a compressor cylinder, 11 a piston and 12 a discharge valve. A pipe or pipes 13, preferably as short as possible, connects the compressor with the pulsation damper which in this form consists of an outer shell 14 and an inner tube 15 having one end closed as at 16. This tube passes out of the end of the outer shell as at 17 and connects with the piping system into which the compressed gas is delivered. The inner tube is provided with one or more longitudinal rows of perforations, which may be arranged in a straight line as shown, in a spiral or in an irregular pattern.

As piston 11 moves toward the right, pressure increases in clearance space 19 until the discharge valve 12 opens against the back pressure in the piping system. The sudden opening of the discharge valve creates a pressure wave which, unless otherwise damped, travels away from the compressor until it is absorbed by friction or the resilience of the discharge piping. In the use of the device illustrated in Fig. 1,

this wave is transmitted along the length of space 20 between shell 14 and tube 15. As the perforations 18, each of relatively small area, lie at progressively increasing distances from the point of initiation of the wave, there is a pressure surge through each perforation as it is reached, and the pressure wave within the outer shell decreases in intensity until at the farther end of the shell it has disappeared. The dotted line 21 in this figure represents such waves, A, B, and C, at three stages of dissolution.

The minor waves created within the inner tube 15 by the surge of pressure through adjacent perforations travel toward each other and do not synchronize. In consequence, provided the number of perforations be sufficient, the flow of gas from the outlet end of the inner tube is substantially or entirely free from pressure pulsation.

A slight modification of the above described structure, adapted particularly to large compressor units, is illustrated in Figs. 2 and 3 in which the various elements are numbered as in Fig. 1. In this form, the clearance space 19 of the compressor is connected with the outer shell 14 by a plurality of downcomers 13-13, spaced along the length of the shell. The general directions of gas flow through the shell, perforations and inner tube are indicated by arrows. As shown in Fig. 3, a plurality of rows of perforations are so placed as regards the line of attachment of the downcomers that there is a minute time interval between the surges through circumferentially spaced perforations as well as between those longitudinally spaced. Thus the pressure surges and the minor waves created by them within the inner tube are out of step in both directions of wave propagation.

In practice it has been found that the pressure drop across the perforated area required to produce substantially complete suppression of pulsation, even at compression pressures as high as 800 pounds gauge, need not exceed one to two pounds per square inch. Neither the number nor the spacing of the perforations is critical, but the free area must be divided among a considerable number of perforations separated by appreciable distances, and these must be so arranged that they lie at progressively increasing distances from the point or points at which the pressure wave enters the outer chamber. In the form of Fig. 1 the compressor discharge enters the chamber at one end and the pressure wave travels through its entire length. In the form of Fig. 2, in which the compressor discharge enters at spaced points, the pressure waves initiated at adjacent points of entry travel toward each other, but the flow of gas through the inner tube is constantly in one direction.

The concentric arrangement of inner and outer tubes shown in Figs. 1 to 3 is convenient but not essential. Fig. 4 illustrates in cross section a modified form in which a tube 14 is divided into two chambers 23 and 24 by a septum 22 having one or more lines of perforations 18. The basic requirement is for a chamber receiving the compressor discharge, a chamber communicating with the discharge piping system, and a septum separating the chambers and provided with perforations arranged at progressively increasing distances from the points at which the compressor discharge enters the receiving chamber. These requirements may be met in numerous modifications of form.

A characteristic of this structure which distinguishes it sharply from the prior art pulsation

dampeners of which I am aware is that its proper functioning is substantially independent of any consideration of volume. In all previous dampener structures known to me, dependence is placed largely on the elasticity of the compressed gas to absorb pressure pulsations, and that principle becomes effective only when the retained volumes are very large. In the device herein described the cross sectional areas of the passages through the two chambers should be such as to avoid any restriction of gas flow other than that afforded by the perforations, in other words each may be no greater in area than the discharge piping into which the device delivers, producing a structure of extreme compactness at a very small fabrication cost.

I claim as my invention:

1. Apparatus for suppressing pulsations in a stream flowing under pressure comprising an elongated gas-tight chamber having inlet and outlet openings therein, an elongated conduit disposed within said chamber having the discharge end thereof extending in pressure-tight arrangement through the outlet opening of said chamber, said conduit being provided with a plurality of openings through the walls thereof at points spaced longitudinally of said conduit as the sole means for intercommunicating flow between said chamber and conduit, means for introducing a pulsating flow of gas under pressure through an inlet opening of said chamber so as to align the resultant wave pattern in said gas longitudinally of said chamber, said gas passing through said openings into the conduit and out of the discharge end thereof at substantially constant pressure.

2. Apparatus for suppressing pulsations in a stream of flowing gas comprising an elongated gas-tight chamber having inlet and outlet openings therein, an elongated conduit disposed within said chamber having the discharge end thereof extending in pressure-tight arrangement through the outlet opening of said chamber, said conduit being provided with a plurality of openings through the walls thereof at points spaced longitudinally of said conduit as the sole means for intercommunicating unidirectional flow between said chamber and conduit, means for introducing a pulsating flow of gas under pressure through an inlet opening of said chamber so as to align the resultant wave pattern in said gas longitudinally of said chamber, said gas passing through said openings into the conduit and out of the discharge end thereof at substantially constant pressure.

3. Apparatus for suppressing pulsations in a stream of gas flowing under superatmospheric pressure comprising an elongated gas-tight chamber having inlet and outlet openings therein, an elongated cylindrical conduit disposed within said chamber having the discharge end thereof extending in pressure-tight arrangement through the outlet opening of said chamber, said conduit being provided with a plurality of openings through the walls thereof at points spaced longitudinally of said conduit as the sole means for intercommunicating flow between said chamber and conduit, means for introducing a pulsating flow of gas under pressure through an inlet opening of said chamber so as to align the resultant wave pattern in said gas longitudinally of said chamber, said gas passing through said openings into the conduit and out of the discharge end thereof at substantially constant pressure.

4. Apparatus for suppressing pulsations in a

stream of gas flowing under pressure comprising an elongated gas-tight chamber having inlet and outlet openings therein, an elongated cylindrical conduit disposed within said chamber having the discharge end thereof extending in pressure-tight arrangement through the outlet opening of said chamber, said conduit being provided with a plurality of openings through the walls thereof at points spaced longitudinally of said conduit as the sole means for intercommunicating unidirectional flow between said chamber and conduit, means for introducing a pulsating flow of gas under pressure through an inlet opening of said chamber so as to align the resultant wave pattern in said gas longitudinally of the chamber, said gas passing through the openings and into the conduit in a direction substantially normal to the direction of flow through the conduit, and said flow through the apparatus being at substantially constant pressure.

5. Apparatus for suppressing pulsations in a stream of flowing gas comprising an elongated gas-tight chamber, a partition member disposed longitudinally of the chamber to divide said chamber into separate elongated entrance and discharge portions, said partition having a plurality of openings therethrough at spaced points along said partition as the sole means for intercommunication between said entrance and discharge portions, means for introducing a pulsating flow of gas under pressure into said entrance portion so as to align the pulsating wave movement in said gas longitudinally of said entrance portion, said gas passing through said openings and into said discharge portion in a direction substantially normal to the direction of flow through the discharge portion, and said flow through the apparatus being at substantially equal pressure.

6. Apparatus for suppressing pulsations in a stream of flowing gas comprising an elongated gas-tight chamber, a partition member disposed longitudinally of the chamber to divide said chamber into separate elongated entrance and discharge portions, said partition having a plurality of openings therethrough at longitudinally

spaced points along said partition as the sole means for intercommunication between said entrance and discharge portions, means for introducing a pulsating flow of gas under pressure into said entrance portion so as to align the pulsating wave movement in said gas longitudinally of said entrance portion, said gas passing through said openings and into said discharge portion in a direction angularly disposed to the direction of flow through the discharge portion, and said flow through the apparatus being at substantially equal pressure.

7. A method for suppressing pulsations in a stream of flowing gas comprising the steps of passing said pulsating stream of gas into a first elongated zone wherein the wave movement in said gas is aligned longitudinally of said zone, dividing said stream into a multiplicity of minor streams flowing in directions substantially normal to the direction of wave movement in said first zone, said division being effected at points varying in distance from the point of gas introduction into said zone, and recombining said minor streams in a final discharge zone to form a second stream of gas flowing out of said zone to a point of discharge and substantially in a direction normal to the direction of flow of said minor streams.
